MARINE STRUCTURE

John E. Byrne, Dallas, Tex., and William S.
Housel, Ann Arbor, Mich.

Application March 20, 1946, Serial No. 655,842

14 Claims. (Cl. 114—43.5)

1
The present invention relates to marine structures and, more particularly, provides such structures which include a floating runway of such length and width as to serve as a flight deck for landing, servicing, and takeoff operations of planes of modern design and size.

The principal objects of the present invention are to provide such structures in which, generically, the runway is composed of a succession of floatable units, hereinafter referred to as barges, which are connected together in end-to-end relation, so that they may be operated as a level, rigid runway or as a flexible chain; to provide such structures in which the connections between the individual barges are separable, so that the individual barges may be separately maneuvered or otherwise used; to provide such structures wherein the connections between the barges supply strength in moment and shear equivalent to that of the barge cross section and at the same time provide for rapid transition from the rigid to the flexible condition, all with a minimum number of operations to be performed afloat; to provide structures wherein the individual barges are provided with propulsion equipment, so that they may move under their own power from the point of construction to any area of military or other operation; to provide such structures which, though relatively light in weight and economical of manufacture and assembly, have sufficient strength to enable the runway to be operated as a level rigid structure in a normal sea and as a flexible chain under extreme weather conditions; and to provide such structures which, in certain aspects, constitute improvements on and modifications of the inventions disclosed and claimed in the prior co-pending applications Serial Numbers 438,051 now Patent No. 2,399,202 dated April 30, 1946, and 452,398 now abandoned, filed respectively April 7, 1942 and July 27, 1942, by the present applicant Byrne.

With the above as well as other and more detailed objects in view, which appear in the following description and in the appended claims, preferred but illustrative embodiments of the invention are shown in the accompanying drawings, throughout the several views of which corresponding reference characters are used to designate corresponding parts and in which:

Fig. 1 is a diagrammatic plan view of a runway comprising a succession of barges embodying the invention;

Figs. 2 through 6 are diagrammatic views in side elevation showing the behavior of the pres-

ent structure under, respectively, rigid and flexible conditions, and when subjected to varying wind velocities and wave magnitudes;

Fig. 7 is a plan view of a unit or barge embodying the invention;

Fig. 8 is a view in side elevation, partly in section, of the structure of Fig. 7;

Fig. 9 is a view in end elevation, partly in section, of the structure of Fig. 7;

Fig. 10 is an enlarged view in horizontal section, taken along the line 10—10 of Fig. 8;

Fig. 11 is an enlarged view in longitudinal section, taken along the line 11—11 of Fig. 7;

Fig. 12 is a view in vertical, transverse section taken along the line 12—12 of Fig. 7;

Fig. 13 is a fragmentary view in vertical section showing details of construction of one of the pontoons which are used to form the buoyant system of the present structure;

Fig. 14 is a fragmentary view in perspective of one of the aforesaid pontoons;

Fig. 15 is a fragmentary view in vertical section of an alternative flooring or decking arrangement;

Fig. 16 is a view in vertical, longitudinal section taken along the line 16—16 of Fig. 7;

Fig. 17 is a view in vertical, longitudinal section taken along the line 17—17 of Fig. 7;

Fig. 18 is a view in vertical elevation taken along the line 18—18 of Fig. 16;

Fig. 19 is a view in vertical, transverse section taken along the line 19—19 of Fig. 16;

Fig. 20 is a view corresponding generally to Fig. 16, but showing the upper portions only of the structure and depicting its behavior under flexible conditions;

Fig. 21 is a fragmentary view in end elevation taken along the line 21—21 of Fig. 8;

Figs. 22 and 23 are views of a modified construction of coupling means;

Fig. 24 is a view in vertical, longitudinal section of another modification of coupling means;

Fig. 25 is a view in vertical, longitudinal section of a further modification of coupling means;

Fig. 26 is a fragmentary view in vertical, longitudinal section of an additional form of coupling means;

Fig. 27 is a diagrammatic, plan view showing operating means which may, if desired, be provided to forcibly separate the barges during parting operations;

Fig. 28 is a fragmentary view in vertical section showing additional details of the just-mentioned parting mechanism;

Fig. 29 is a diagrammatic view showing fluid

connections between the hydraulic rams associated with the individual barges;

Fig. 30 is a diagrammatic, plan view showing further details of certain of the operating elements associated with the individual barges;

Fig. 31 is a diagrammatic view in vertical, longitudinal section showing certain additional ones of the operating elements associated with the individual barges;

Fig. 32 is a diagrammatic view in perspective of a further arrangement of barges;

Fig. 33 is a diagrammatic view illustrating the use of the present structure as a landing platform or floating dock;

Fig. 34 is a fragmentary, diagrammatic, vertical, sectional view showing another modified construction;

Fig. 35 is a plan view of one of the damping assemblies of the embodiment of Fig. 34 showing the coacting parts carried by the abutting ends of two barges, the barges being fragmentarily illustrated;

Figs. 36 and 37 are diagrammatic, side elevational views showing the action of the modified damping means when the articulated joints are located over the crest and over the trough of the waves respectively; and

Fig. 38 is a cross-sectional view taken substantially on the line 38—38 of Fig. 34, and looking in the direction of the arrows.

It will be appreciated from a complete understanding of the present invention that, in a generic sense, the improvements thereof may be embodied in marine structures intended for widely different purposes, and usable under widely differing conditions. Illustrative uses of the invention includes seadromes to accommodate land- or seaplanes, breakwater or other harbor facilities, loading docks, and the like. It will be understood that the disclosure herein of specific constructions is to be taken in an illustrative and not in a limiting sense.

Referring to the more or less diagrammatic views, Figs. 1 through 6, a runway 50 is illustrated as being comprised of a succession of preferably identical units or barges 52 connected together in end-to-end relation, junctions between adjacent barges being spanned by the hereinafter described platforms or bridges 54. The individual barges 52 are interconnected by the hereinafter described couplings generally designated 56 which, in accordance with the present invention, are selectively adjustable, so as to hold the barges 52 in relatively rigid relation to each other as shown in Fig. 2, or to articulate them so as to produce a flexible chain of barges as shown in Figs. 3 through 6. The upper surfaces or decks of the individual barges may be variously arranged as hereinafter described, to constitute a nonskid flight deck suitable for landing, servicing, and takeoff operations of planes of modern design and size.

As will be appreciated, the individual barges may be proportioned to suit the particular operating conditions contemplated, and the number of barges to be included in a given runway may vary widely. By way of example, barges approximately 100 feet in width and 156 feet in length have been found suitable both from the standpoint of affording sufficient area for landing, servicing and takeoff purposes, and from the standpoint of ability to withstand actual wave conditions which may be expected in service. Figs. 1 through 6 are scaled to such dimensions, it being noted that a runway composed of six

such barges affords a landing strip of somewhat less than a thousand feet in length. The behavior of such a runway under actual wave conditions is diagrammatically shown in Figs. 2 through 6, these illustrated wave conditions being based on the "Trochoidal wave theory" as set forth in "Theoretical Naval Architecture" by Attwood and Pengally, and in "Principles of Naval Architecture" by Russell and Chapman.

Figs. 2 and 3 are both based upon wind velocities of approximately 25 miles an hour, and waves of approximately 260 feet in length and approximately 17 feet in amplitude. Analysis shows that the hereinafter-described barge constructions may safely be operated in the rigid relation shown in Fig. 2 under conditions of at least such severity, or alternatively they may be articulated as shown in Fig. 3. The arrangement is such that the runway may be quickly and readily changed from the rigid to the flexible conditions or vice versa. Thus, for example, the runway may be operated in a continuously rigid condition under weather conditions up to a certain severity; under conditions of somewhat greater severity than those shown in Figs. 2 and 3, the runway may be made rigid during the course of landing or takeoff operations, and may be altered to the flexible condition during intervals between landing or takeoff operations.

Fig. 4 is illustrative of wind velocities of approximately 31 miles per hour, and waves of 400 feet in length and 20 feet in amplitude. Under these conditions the wave span from crest to crest is in excess of the over-all length of two barges, making it preferable to maintain the runway in a flexible condition. Under these weather conditions, however, the flexibility of the runway does not materially interfere with landing or takeoff operations, since the maximum angle between successive barges is relatively small. Similar comments apply to Figs. 5 and 6, which depict, respectively, wind velocities of 37 and 44 miles per hour and waves of 575 and 800 feet in length and of 25 and 30 feet in amplitude. Under these conditions the runway can efficiently handle both landing and takeoff operations while in a flexible condition, and the flexible chain of barges is able to weather the wind and wave conditions without being overstressed.

The present arrangement further provides that the individual barges may be readily separated from each other and allowed to individually weather storm conditions. Consequently, in the event the weather conditions become so severe as to render it inadvisable to maintain the articulated chain, the barges may be separated from each other and thereafter recollected and formed into unit relation. In this connection it is noted that in the preferred practice of the invention, the individual barges are provided with propulsion equipment, so that they may operate under their own power while so separated. The provision of the propulsion equipment also enables the barges, individually and when coupled, to maneuver under their own power, thereby maintaining seaway and providing perfect orientation with the prevailing wind.

Referring particularly to Figs. 7 through 15, the individual units or barges are illustrated as embodying, with certain improvements, the inventions described and claimed in the present applicant's aforesaid prior applications. More particularly, each barge is made up of a series of longitudinal trusses 60, transverse trusses 62, a deck

64, and a buoyant system composed of a plurality of air- and water-tight cells or compartments 66. The longitudinal and transverse trusses are arranged in a box-type or gridiron assembly which defines a plurality of bays, each of which bays accommodates, as shown, a pair of cells 66.

The trusses support the deck 64 at a suitable elevation above the upper surfaces of the cells 64, the vertical spacing thus afforded being, of course, variable to suit different operating conditions. In the illustrated case in which, for example, the bays may be approximately twelve feet on a side, the just-mentioned spacing is of the order of nine feet, the vertical heights of the cells being approximately six feet. Such proportioning is advantageous in that the resulting structure has a very shallow draft, rendering it a very difficult torpedo target, and also has a low-line profile, making it relatively indistinguishable, except at close range. The multiple cell arrangement is advantageous, as will be recognized, in that destruction of a considerable number of such cells is needed in order to render a particular barge unserviceable. As an example, a barge embodying the present invention may be maintained afloat under reasonable deck-loading, even though up to approximately forty per cent of its cells have been punctured.

The very shallow draft is further advantageous in that it enables the present structure to navigate or rest in very shallow water at low tide or in shallow rivers or to ride over reefs or similar obstacles. This ability enables practical use of the structure as a floating dock, which relation is indicated in Fig. 33.

As will be understood, the relatively clear space between the tops of the cells and the underside of the deck may be utilized for various practical purposes, such as affording space for crews' quarters, supplies, repair parts, and for the housing of mechanical equipment. When so utilized, it is preferred to enclose the sides and ends of this space, as by means of side panels 68, and end half-panels 69, which may, for example, be formed of sheet metal or the like.

Each longitudinal truss 60 comprises upper and lower chords 70 and 72 which may be and preferably are formed of T members, compression vertical members 74 illustrated as being lengths of pipe, and tension diagonals 76 illustrated as being formed of strip steel. Upper and lower ends of the pipe section verticals 74 are slotted parallel to the plane of the truss, and the webs of the T chords are received in these slots. Upper and lower ends of the diagonals 76 are secured to the webs of the chords and are also secured together at their respective intersecting points. All the just-mentioned connections are preferably completed by welding.

The transverse trusses are similarly formed, having upper and lower T chords 80 and 82, pipe-section verticals 84, and strip-steel diagonals 86. The individual chords 80 and 82 extend between laterally adjacent longitudinal trusses and have their ends rigidly secured as by welding to the adjacent longitudinal T-chord members.

The connections between the transverse and longitudinal trusses are reinforced by upper and lower series relatively heavy, horizontal gusset plates 88. The upper series of plates 88 overlie and are welded to the flanges of the upper chords 70 and 80. Similarly, the lower plates 88 underlie and are welded to the flanges of lower chords 72 and 82. The resulting arrangement will be

recognized as a Vierendeel grid system which in this case is reinforced by the diagonals 76 and 86.

Preferably, and as shown, those parts of the individual bays which are occupied by the associated pairs of pontoons 66 are provided with vertical corner fenders 90 and horizontal top and bottom fenders 92. The vertical fenders 90 may be and preferably are directly secured to the pipe-section verticals. The lower fenders 92 rest upon the flanges of the associated chords 72 and 82. The upper fenders 92 are secured to frame members 94 which interconnect the pipe section verticals 60.

All the cells 66, except those in the rows at the respective ends of each barge, are preferably of rectangular form, constructed as shown in Figs. 13 and 14. All sides of these rectangular cells are preferably composed of conventional sheet metal structural members having relatively wide webs 100 and main and auxiliary flanges 102 and 104. Preferably, and as shown, the webs 100 are depressed, as indicated at 106, to form a seat to receive the marginal edge of the web of the next successive member. All joints by the successive members are preferably completed by welding, as indicated at 108 in Fig. 13. As illustrated, the individual webs 100 may be provided with reinforcing ribs 110. The resulting pontoons or cells, although relatively light in weight, are both air- and water-tight and are very strong. The cells 66 associated with the end rows of each barge preferably duplicate those described above, with the exception that these cells have one angled side 112.

The flight deck 64 is preferably continuous over the surface of each barge and is arranged to provide a nonskid surface suitable for landing and take-off purposes. This deck may also be provided, of course, with conventional instrumentalities (not shown), such as cleats, chocks, and other holding devices suitable to retain a plane in a parked position along the runway. The deck is made continuous over adjacent ends of the barges by means of the previously-mentioned deck sections or bridges 54, described more in detail in connection with Fig. 16. The deck 64 may be variously constructed, a laminated cellular arrangement composed of wood or the like being shown in Fig. 8, and a sheet steel arrangement comprising decking 122 supported on channel members 124 being shown in Fig. 15.

In the broader aspects of the invention any of a relatively wide variety of couplings may be utilized to connect the successive barges together in end-to-end relation, as a rigid structure, or as a flexible chain. Several such couplings are shown in the present application. The arrangement shown in Figs. 16 through 21 is now preferred and embodies a separable hinge which extends continuously across the junction between successive barges. Referring particularly to these figures, as well as to Figs. 7, 8, and 9, the end bays of each barge are provided with supplementary diagonal bracing members 130. The barge ends are provided with horizontal supporting members 134. It is noted that these members extend entirely across the end of each barge approximately centrally, the right-hand half of Fig. 9 being a view in end elevation and the left-hand half thereof being a view in transverse vertical section through a barge.

As best shown in Fig. 16, the supporting member 134 at one end of each barge is provided with a continuous, transverse throat or socket member 136. The member 134 at the other end of each

7
barge is provided with a continuously-extending, complementary, tubular member 138 which functions as a hinge pin. As will be understood, the sockets 136 of one barge receive the pins 138 of the next and support the same against relative cocking of the barges about the longitudinal axes thereof while permitting flexing movements thereof about the axis of the hinge connection. The abutting ends of the barges are also provided with fenders 141 which are normally spaced from each other, but which limit the degree to which the barges may flex relative to each other.

As shown, the members 138 are retained within the sockets 136 by heavy but resiliently mounted chains 140, one end of each chain being separably coupled to a take-up spring 142 and the other end thereof being trained over an idler sheave 144 and connected to a winch or other operating unit 146, as shown in Fig. 30. As also appears in Fig. 30, each end of each barge is preferably provided with a series of winches 146 arranged in alternately successive bays, and each winch handles a pair of chains 140. The winches at the opposite ends of the bays are arranged in staggered relation. It will be understood that the individual chains pass through enlarged registering openings in the hinge members 136 and 138, the openings 150 associated with member 136 being shown in Fig. 21.

In the illustrated embodiments of the present invention, the means for selectively rendering the barge connections either rigid or flexible comprises upper and lower series of fluid pressure-controlled and -operated rams or buffers 162, a hydraulic fluid such as oil being the preferred medium. As most clearly appears in Fig. 16, the decks 64 terminate short of the ends of their associated barges, leaving a free space to accommodate the successive pairs of rams. Various numbers of buffers may be utilized as will be understood, although at least one should be located above and another below the hinged coupling (136, 138, etc.). In the illustrated arrangement the abutting ends of the barges are substantially rectangular, and one buffer is provided for each longitudinal truss 60. The buffers may thus be considered as arranged in pairs, each pair comprising one upper and one lower buffer.

The cylinders 160 are rigidly secured to the associated truss chords, and the buffer elements 162 thereof project outwardly of the cylinders for end-to-end engagement. The corresponding cylinder spaces of the upper and lower units of each pair of bumpers are interconnected, the cylinder spaces at the outer ends of the cylinders of each pair being connected by a cross-connecting line 181, and fluid travel between the units through this line being controlled by the metering valve 183. The inner ends of the upper and lower units of each pair are similarly connected by the cross-connecting line 180, which contains the metering valve 182. The metering valves may be adjusted to control the relative damping effect, or may be tightly closed to trap the liquid and lock the units.

Each cylinder contains a piston 163 rigidly attached to the inner end of the bumper element 162 and yieldably centered in the cylinder by a spring 165. It will be apparent that the springs may be arranged to act in compression only, as shown, since when the abutting barges are coupled as depicted in Fig. 16, the abutting units of coupled barges are engaged and the springs of the mating bumper units oppose one another.

Hydraulic fluid is supplied to the inner ends of

the cylinders by feed pipes 170 and branch connecting pipes 166 connected to the individual cylinders, each of the branches 166 containing a check valve 167 so that uncontrolled cross-connection through the feed pipes cannot occur. The outer ends of the cylinders are similarly supplied through supply pipes 168 and branching connections 164, each of which also contains a check valve 169. Feed pipes 168, 170 are connected directly into supply headers 171, 172, as shown, which are in turn fed from a suitable pump unit 176 which is common to all the rams of a particular barge. The return from each header, when pressure is not applied thereto, is connected to one of the reservoirs 176, 178, one located adjacent each end of the barge. Through suitable diverting valve means, such as is indicated at 179, the fluid may be directed to either of the headers to the exclusion of the other, or to both headers at once. When only the supply pipes 168 are thus under pressure (and the pipes 170 are vented), the bumpers are positively retracted and the springs 165 held under compression. Alternatively, feed line 168 may be vented while pressure is delivered only to feed line 170. Cross-connecting valves 182, 183 are at this time completely closed by hand. The rams are then rigidly projected, and the yieldability of the unit is destroyed by the incompressibility of the liquid and the presence of the check valves 167. When one end of a cylinder is to be vented, the check valves 167 or 169 may be manually opened or rendered ineffective by opening the normally closed by-pass valves 177 or 179.

It will be understood that if it is desired to separate adjacent barges, the ram pistons 162 associated therewith may be retracted, the winches may be operated to let out sufficient chain, and thereafter the respective chain ends may be disconnected from their associated mounting springs 142. The operation of interconnecting a pair of barges is of course the reverse of that just described.

Each bridge 54 which adjustably spans the junctions between adjacent barges comprises a main platform member 200 and an auxiliary platform 202 which overlies and is slidable relative to the associated main platform 200. The auxiliary platforms 202 are hinged to the ends of the associated decks 164, and the main platforms 200 are supported at the ends of the associated barges for movement lengthwise thereof. The supporting connection is preferably a rolling one, and for this purpose each barge end is provided with two series of mounting rollers 204 and 206. These rollers 204 and 206 are carried by bearing members 208 and 210. The bearing members 210 are carried by the end of the end transverse trusses 62, and the bearings 208 are supported by auxiliary structural members 212 which are secured to and extend between adjacent longitudinal trusses. The forward end of each platform 200 rests upon the rollers 206, and the rear end of each platform 200 is provided with a guide or runway which receives the associated rollers 204. This guide or runway is provided by the underside of the platform and by a co-operating channeled member 214, the length whereof of course determines the limits of movement of the associated platform 200. One platform 200 associated with each barge is provided with a hinged connecting member 216, one plate whereof is permanently secured to the corresponding platform and the other plate whereof is separably secured to the platform 200 of the adjacent barge.

Thus, as shown in Fig. 20, when the chain of barges flexes, the platforms 200 of the articulated barges are retained in connected relation to each other and roll inwardly or outwardly relative to the end of the associated barge. At all times, therefore, a substantially continuous runway is provided.

In the modified embodiment of the invention shown in Figs. 22 and 23, the coupling means is replaced by a series of rigid metal pads 436 mounted upon the ends of each barge in aligned vertical positions and spaced outwardly therefrom by individual supports 432. The pads are perforated as at 437 for passage of the chain 440 therethrough. When the chains are drawn up, the pads of the articulated barges are forced into abutting relation and co-operate with the chain to form the coupling means, pivotal movement of the barges merely flexing the chain.

In the further modification shown in Fig. 24 the coupling means is constituted by a succession of spaced ball-and-socket joints, each comprising a socket 220 and a ball 222 which is receivable therein. The sockets 220 and balls 200 may be and preferably are secured to the associated ends of the barges in a manner similar to that described above, except that the horizontal supports 134 are reinforced by verticals 132. In this instance the chains 140 pass through registering openings in the sockets and the balls. The complete assembly is shown in Fig. 24, and the supporting structure, with the balls and sockets removed, is shown in Figs. 22 and 23.

For certain types of service, the controlled flexing afforded by the flow of regulating fluid described in connection with Fig. 16 is not required. In such instances the arrangement of Fig. 25 is suitable. In Fig. 25 a hinging arrangement similar to that described in connection with Fig. 16 is utilized, comprising a socket 136 and a pin 138. In this instance one end of each barge is provided with upper and lower fixed fenders 240. The other end of each barge is provided with a swingable chock 242. The chocks 242 are carried by arms 244 which in turn are pivoted to the associated barge. Rams 246 may be provided to swing the chocks 242 between the dotted-line retracted position and the active full-line position in which they fill the spaces between the fenders 240, 241 and block pivotal movement of the barges.

With the chains 140 drawn up tightly and the chocks in the full-line position of Fig. 25, an entirely rigid connection is afforded, as will be understood. On the other hand, by retracting the chocks, free flexing of the barges relative to each other is permitted, such flexing taking place about the axis of the hinge connection and being limited by engagement between the fenders 240, 241.

Fig. 25 also illustrates the use of centering springs 243 for the rolling bridges, which of course also may be incorporated in the other embodiments disclosed herein. The springs 243 act between the ends of the associated bridges and the corresponding barges.

In certain other instances it is found that the flexing feature may be omitted, the arrangement being such that the barges, if interconnected at all, are rigidly interconnected. Referring particularly to Fig. 26, a hinge connection comprising members 136 and 138 described above is utilized. In this instance, when the chains 140 are drawn up, fixed upper and lower fenders 260 are drawn into engagement with each other, thereby com-

pleting a rigid connection. In such instances also the previously described rolling bridges may be dispensed with, and the portions 136, 138 serve merely to guide the barge ends into and maintain them in properly aligned relation.

It will be understood that all hinged or other separable connections between the barges are so designed as to have, when in rigid relation, the same strength in moment and in shear as is afforded by other transverse sections through the barge.

In certain cases it is desirable to provide special equipment to facilitate the operation of parting adjacent barges, which equipment is illustrated in Figs. 27 and 28. In these figures a pair of parting members are provided at one end of each barge for co-operation with fender plates 292 of relatively large area secured at the opposite end of the adjacent barge. The members 290 are normally retracted, as shown in Fig. 28, but may be projected by means of rack-and-pinion actuating means so as to bear against the fenders 292 and forcibly separate the barges (after release of the coupling chains). Suitable means, such as a motor 294, may be utilized to operate the members 290 in both projecting and retracting directions.

It is proposed in general to provide each barge with its own propulsion equipment, Diesel equipment being preferred. Alternatively, only certain of the barges may be provided with propulsion equipment and may be utilized to tow other barges. For such towing operations the barges of a series may be rigidly or flexibly interconnected, or may be relatively widely separated, the towing connection being afforded by the previously described chains, or other means. A suitable arrangement for accommodating the propulsion equipment is shown in Fig. 31 in which a propulsion unit 280 is disposed in a depressed pocket 282. In this figure the rudder is indicated at 284.

In the modified construction shown in Figs. 34-38 inclusive, the damping means consists of a plurality of cylinders 360 each trunnioned for pivotal movement about an athwartship axis near one end of one of the barges, as in the cradle 362, a co-operating piston 364 being slidably fitted in the cylinder and having an extension 365 similarly trunnioned in a cradle 366 attached to the adjacent barge. In order to provide an uninterrupted full width deckway across the articulated barges, the upper damping assemblies are mounted outboard as upon outrigging 368. Only two upper damping assemblies are used, and these must of course be of sufficient size and resistance to do the work of the multiple unit systems, involving eight or more upper units, previously described. In the interests of standardization, these heavier units, mounted at the corners only, are used as bottom buffers also in the embodiment shown, although it will be recognized that a larger number of smaller units might be employed as bottom buffers as in the embodiments previously described. A central pivot joint is provided by the portions 136, 138, etc., which may correspond to those shown in the embodiment of Fig. 16.

The pivot pin 367 by which each piston is connected to its barge may be removable when the barges are to be uncoupled, so that the cylinder and piston may remain assembled as a unit. The interiors of both the cylinder and piston are hollow, and a plurality of metering orifices 382 are formed in the piston head, the interior of the assembly being filled with a suitable liquid which,

11

since it must flow through the metering orifices and upon telescopic movement of the cylinder and piston, serves to damp the oscillations of the barges about the coupling joint axis.

When it is desired to lock the barges against pivotal movement, rigid connecting links 342 are utilized, connected at their ends as by pins 344 to suitable lugs 345 carried by lateral extensions of the cradles 362, 366. Pins 344 are of course removable when it is desired to uncouple the links to permit pivotal movement of the barges. Each cylinder-and-piston assembly 360, 364 may constitute a self-contained unit, and it will be seen that no spring means is required unless it is desired to impose increasing resistance to increasing angular displacement of the coupled barges. When no springs are incorporated, it is a simple matter, if it is desired to disconnect the damping means and permit free articulation of the barges, to remove the pins 367 and secure the pistons 364 in retracted positions in their cylinders, as by means of simple thumb screws 385.

Referring particularly to Fig. 32, it will be recognized that although the preceding description has dealt particularly with a runway comprising a single series of barges arranged in end-to-end relation, various other interconnected arrangements may be utilized. For example, parking barges such as 300 may be secured along the sides of a particular runway 50, at desired spacings. Also, a series of runways 50 may be arranged to define a partially enclosed or sheltered area. Although only certain specific embodiments of the invention have been described in detail, it will be appreciated that various further modifications may be made without departing from the spirit and scope of the invention.

We claim:

1. An articulated floating structure comprising a pair of float elements, coupling means for said elements preventing separation thereof but permitting pivotal movement therebetween, yieldable damper means interconnecting said elements at points spaced from said coupling means to yieldably oppose and control such pivotal movement, and means for locking said damper means to prevent pivotal movement between said elements.

2. Means for articulating a pair of floating structures comprising coupling means for pivotally securing together adjacent portions of said structures, said coupling means being located substantially centrally of the vertical dimension of the abutting areas of said structures, yieldable means incorporated in said coupling means, a plurality of yieldably projected buffers carried by each of said structures engageable with corresponding opposed buffers carried by the other articulated structures, at least one of said buffers being located above and another below said coupling means and selectively operable means for holding said buffers in a desired position to hold said structures against relative movement.

3. In combination, a pair of floatable structures, means for articulating and controlling the relative movement of such structures, comprising pivotal coupling means located substantially centrally of the abutting portions of such structures and extending transversely thereof to permit pivotal movement of said structures with respect to a transverse axis while preventing pivotal movement about other axes, a flexible holding element extending between and preventing separation of said structures and extending

12

through said coupling means substantially at the axis of pivotal movement, and locking means interconnecting said structures at points spaced from said coupling means to hold the structures against relative movement.

4. Means as set forth in claim 3 including a pair of such locking means, one located above and another below said coupling means, said locking means including cylinder and piston portions slidably one within another during pivotal movement of the floatable structures, fluid conducting means connecting said locking means and permitting fluid flow from one to the other of said locking means during such pivotal movement, at least a portion of said conducting means being restricted to limit the rate of such fluid flow and thereby control the effective resistance offered by said damping means, and means to close said conducting means to place said locking means in locking condition whereby the structures are held against relative movement.

5. In combination, a plurality of floatable structures, each such structure being at least 150 feet in length and connected in end-to-end relation to provide a landing strip for land-type planes, means for articulating and controlling relative pivotal movement of such structures, comprising pivotal coupling means located substantially centrally with respect to the vertical dimensions of the abutting portions of such structures, said structures having decks, selectively operable damping means interconnecting said structures at a point above said coupling means and below the level of said decks, means for locking said damping means whereby the structures are held against relative movement for use under conditions in which the crest-to-crest distance of successive waves is less than 400 feet, said locking means being releasable so that at crest-to-crest distances above 400 feet said damping means may be rendered effective whereby the structures may follow generally the contour of the large waves when providing a surface for landing and take-off of planes, and flexible bridging means connecting the decks of said structures and extending over said damping means.

6. In combination, a pair of floatable structures, means for articulating and controlling relative movement of said structures, comprising pivotal coupling means located substantially medially of the abutting portions thereof, a plurality of damping means interconnecting said structures at points spaced from said coupling means to resist pivotal movement of the structures, each of said damping means including interfitting cylinder and piston portions, means tending to center each piston in its cylinder, means for supplying hydraulic fluid to each of said cylinders at a point upon each side of the piston therein, including a feed line system having branches extending to each end of each cylinder and a check valve incorporated in each of said branches.

7. In combination with means as set forth in claim 6, means for rendering said check valves ineffective, whereby a free flow of fluid through said branches may occur between cylinders connected to the same feed-line system.

8. Means as set forth in claim 6 in which one of said damping means is located above and another below said coupling means, means for rendering said check valves ineffective, whereby a free flow of liquid between said damping means connected to the feed-line system may occur, and separate means including a manually controllable

13

metering valve also interconnecting said cylinders.

9. Means for articulating a pair of floating structures including a plurality of damping devices, each of said devices comprising a plurality of relatively movable parts, means imposing predetermined opposition to relative movement of said parts, said last-named means including a hydraulic system comprising a source of fluid under pressure and means for delivering fluid to said devices or withdrawing the fluid from such devices at will to control the damping action of said devices.

10. Means for articulating a pair of floating structures including a plurality of damping devices, each comprising a plurality of relatively movable parts adapted to be connected between and to control the relative movement of said floating structures, means including a hydraulic chamber for opposing relative movement of the parts of said devices, and a central fluid supply system connected to all of said chambers, including means for varying the fluid supply to said chambers to control the damping action of said devices.

11. In combination with means as set forth in claim 10, means for withdrawing the fluid from said devices to free said parts to permit virtually unrestrained movement thereof and resultantly permit substantially unrestricted articulating movement of said floating structure.

12. In combination with means as set forth in claim 10, means for trapping a quantity of fluid in each of said chambers under sufficient pressure substantially to lock said parts against relative movement and thereby rigidly hold said floating structures in desired position with respect to one another.

13. In combination, a pair of floatable structures, means for articulating and controlling relative movement of such structures, comprising pivotal coupling means located substantially cen-

14

trally of the abutting portions of such structures, said coupling means normally permitting pivotal movement between said structures, and locking means interconnecting said structures at points spaced from said coupling means, whereby said structures may be locked into a rigid body, said locking means including fluid controlled portions connectible to the respective structures.

14. In combination, a pair of floatable structures, means for articulating and controlling relative movement of such structures, comprising pivotal coupling means located substantially centrally of the abutting portions of such structures, locking means interconnecting said structures at points spaced from said coupling means whereby said structures may be locked into a rigid body, and hydraulic control means for said locking means, each of said locking means including a buffer element, means yieldably projecting the same whereby it may oppose pivotal movement of said structures, and means for retracting said buffer elements.
